MACHINE FOR EQUIPPING BOX PARTS
WITH FASTENING MEANSAlfred L. Rosenmund, Woodport, N. J., assignor
to Stapling Machines Co., a corporation of
Delaware

Application September 16, 1940, Serial No. 356,900

2 Claims. (Cl. 140—93)

This invention relates to machines for equipping wired box parts with fastening means.

It is an object of the invention to provide improved wire-manipulating mechanisms for forming a loop or bight on a wire secured to a box part and for perpetuating the loop or bight by driving the end of the wire into the box part.

One illustrative embodiment of the invention is shown in the accompanying drawings, in which—

Figure 1 is a side elevation of a fastener-supplying machine embodying the invention, showing a portion of the right-hand jaw member broken away and the clutch unit omitted for clearness.

Fig. 2 is a top plan view taken on line 2—2 of Fig. 1.

Fig. 3 is an enlarged sectional view of the clutch unit taken on line 3—3 of Fig. 2.

Fig. 4 is a side elevation of the front end of the machine, showing a prong being formed on the binding wire after the wire has been cut to the desired length.

Fig. 5 is an enlarged view of a portion of Fig. 4, showing more clearly the prong-forming operation and the elements involved.

Fig. 6 is an enlarged view taken on the line 6—6 of Fig. 4, showing the cycle of operation slightly advanced, with the prong portion being bent into position to form a bight by parts acting upon it from above.

Fig. 7 is an enlarged plan view taken on the line 7—7 of Fig. 4, showing the bight-forming parts in the same position as in Fig. 6.

Fig. 8 is an enlarged sectional view taken on the line 8—8 of Fig. 4.

Fig. 9 is a front end view taken from the left side of Fig. 4, with some parts in section and others omitted for clearness, showing the means to properly position the binding wire.

Fig. 10 is an enlarged partial front end view showing, in broken lines, an element to position the prong and, in full lines, the driving elements after completion of a driving operation.

Fig. 11 is an enlarged side elevation taken on the line 11—11 of Fig. 10, showing, in broken lines, the prong in position to be driven and, in full lines, the prong driven through the work to be clinched.

Fig. 12 is a partial top plan view of Fig. 11, showing the bight-forming elements returned to their initial position.

Fig. 13 is an enlarged plan view taken on the line 13—13 of Fig. 11, showing the bight-forming elements after the bight has been completed and the prong driven.

Fig. 14 is a partial view, on the same scale as Fig. 11, showing the clinching of the prong and illustrating, by broken lines, the work-supporting table lowered to strip the bight from the forming elements.

Fig. 15 is an isometric view showing a completed fastener having its bight portion located a predetermined distance from the forward edge of the sheet of veneer or plywood.

In Figs. 1 and 2, there is illustrated a machine embodying the invention, the primary object of which is to provide appropriate mechanisms which operate upon the binding wire from above to form a bight and to perpetuate the bight by driving the prong thereof through the veneer or plywood or other suitable material to locate the fastener a desired distance from the edge of the work, as illustrated in Figs. 13 and 15.

The wired box parts to which these fasteners are supplied are made on a box-blank machine which staples the wire to the box parts. As shown in Fig. 15, the box part is designated *a*, the binding wire *b*, and the staple *c*.

Referring again to Figs. 1 and 2, the machine comprises a base *1*, upon which is mounted a right jaw *2* and a left jaw *3*. The left jaw *3* has an upper extension *5* and a lower extension *4*. These extensions *4* and *5* support the mechanisms that operate upon the binding wire *b* to sever it to correct length, to form a prong thereon, to bend the prong portion to bring it over the box part *a* to form a bight, to drive the prong end through the box part, and to clinch the prong end to perpetuate the fastener.

Motion is imparted to a drive pulley *6* rotatably mounted on a main shaft *8* by means of a belt connection to a motor *9*. The drive pulley *6* houses therein a clutch unit (Fig. 3) similar to the clutch unit of United States Patent No. 2,130,486 of September 20, 1938, to E. M. Florcyk. The clutch as shown in Fig. 3 is disengaged from the drive pulley *6*.

Generally, the clutch comprises a member *10* keyed to the main shaft *8*, which carries integrally thereon an ear *11* and an extension *12*, to which is loosely mounted on a pin *13* a member *14* which has secured to its outer surface adjacent the clutching surface *7* of the drive pulley *6* one end of a divided clutch band *15*. Loosely mounted on the keyed member *10* is a flanged collar *16* which supports an ear *18* and an extension *19*, to which a shoe *20* is connected by a toggle link *21*. Secured to the outer surface of the shoe *20* is the other end of the clutch band *15*. A suitable notch is provided in a flange *17*

of the flanged collar 16 which the buffer 23 contacts to disengage the clutch and to cause energy to be stored in a coiled spring 22 which has one end fastened to the ear 11 of the member 10 keyed to the main shaft 8 and has its other end fastened to the ear 18 of the loosely mounted flanged collar 16 (Fig. 3). Thus, when the buffer 23 is moved to the position shown in broken lines in Fig. 3, the coiled spring 22 will be permitted to contract, rotating the flanged collar 16 sufficiently about the member 10 to cause the clutch band 15 to expand and clutch the surface 7 provided therefor in the drive pulley 6.

An appropriate brake unit 24 is provided, which is relatively timed to cause a braking action of the main shaft 8 instantly following the disengagement of the clutch from the drive pulley 6.

A foot treadle 25, loosely mounted on shaft 26, is connected by appropriate linkage and levers to operate the clutch buffer 23 and the brake unit 24 simultaneously. Since the operation of supplying a complete fastener requires only one cycle of the main shaft 8, it is necessary only to press the treadle 25 down to remove the buffer 23 from its engagement with the notch in the flange 17 and at the same time release the brake unit 24 against the action of spring 27 which holds the buffer 23 in contact with the outer surface of flange 17 until permitted to drop into the notch provided therein.

A cam 28 keyed on the main shaft 8 is of such design as to impart an oscillating motion to an upper carriage 38 and to a lower carriage 29 through appropriate connection therewith.

The lower carriage 29 comprises an inverted open framework having two horizontal rods 30 interposed between the end portions. The rods 30 are spaced apart to coincide with bores in members 31 permanently secured to the inside surface of the lower extension 4. A turnbuckle link 32 pivotally secured to the rear of the lower carriage 29 is pivotally secured by a stud 33 to a lever 34 loosely mounted on stud 35 threaded in the inside of the left jaw 3. The upper end of the lever 34 has rotatably mounted thereon a roller 36 which is pressed against the face of the cam 28 by the action of a spring 37 which has one end fastened to the lower part of lever 34 and the other end fastened to the inside of the left jaw 3.

The upper oscillating carriage 38 is similarly controlled. It too comprises an open framework with two conveniently spaced horizontal rods 39 which are housed in bearings in the member 40 secured to the inside of the upper extension 5. A turnbuckle link 41 pivotally secured to the upper carriage 38 is pivotally secured also to a lever 42 by stud 43.

The lever 42, loosely mounted on stud 44 threaded in the inside of the left jaw 3, has its lower portion conveniently angled to present a roller 45, rotatably mounted on the end thereof, to the work face of the cam 28. The roller 45 is held in contact with the cam by the action of a spring 46 fastened to the upper portion of the lever 42 and the inside of the left jaw 3.

Referring to Figs. 1, 2, 4, and 9, and particularly to Figs. 1 and 9, the table provided to support the work consists of two horizontal bars 47 with hangers 48 loosely mounted on shaft 49. The horizontal bar 47 adjacent the outside of the left jaw 3 has an extension to the rear of the machine and is anchored by a spring 50 fastened thereto and to the lower portion of the left

jaw 3. Spaced apart and secured on the top surface at the front end of the horizontal bars 47 are flat cross-members 51 which are also supported by short bars 52 permanently mounted on tie rods 54 extending through each horizontal bar 47 and secured by nuts. The short bars 52 are separated by a spacer 55 which permits a clincher 102 to function freely, as will be described later. A link 56, loosely mounted on the tie rod 54, extends downwardly to connect to an auxiliary foot treadle 57 which is loosely mounted on the shaft 26, its purpose being to pull the table down against the action of the spring 50 at the completion of a fastener-supplying operation.

As shown in Figs. 4, 5, and 8, the lower oscillating carriage 29 has securely mounted on its top surface a straight-motion cam 58 designed to support on its work face a roller 61 loosely mounted on a stud 62 secured in a downwardly extending projection of a support block 60 which carries on its top surface the movable knife 63 and prong-forming die 64, shown clearly in Figs. 5 and 8. The support block 60 has imparted thereto a vertical reciprocating motion through the roller 61 following the contour of the straight-motion cam 58. The support block 60, with the bearing on member 65, also is guided by a rectangular bar 69 and a rod 70, both of which are detachably secured in the housing block 68 and extend downwardly into bearings provided in the support block 60. To insure that the roller 61 follows the contour of the work face of the straight-motion cam 58, there is provided a spring 71 interposed between the bottom surface of the housing block 68 and the bottom of a counterbore in the support block 60, and coiled about the rod 70. There is also provided, to contact with the spring 71 and to serve as a stop member as well, another downwardly-extending portion 66 of the support block 60 which carries in its lower portion a stud 67 adjacent the side of the straight-motion cam 58 to contact a member 59 supported by cam 58, whose beveled contour parallels that of the latter portion of cam 58, preventing the roller 61 from leaving the surface of cam 58 when the support block 60 descends to release the prong on binding wire b from the prong-forming elements.

As shown in Figs. 4 and 9, the housing block 68 secured to the inside surface of the upper extension 5 is relatively located to cooperate with the mechanism just described and to have certain elements that it supports acted upon by a straight-motion cam 72 permanently secured to the under surface of the upper carriage 38. Referring now to Figs. 6 and 7, the under surface of the housing block 68 has detachably mounted thereon a fixed knife 73 which carries a suitable beveled notch 74 in its forward bottom edge adjacent to a detachably-secured forming member 75, both of which coact with the forming die 64 of the support block 60, as shown in Fig. 5. Reference to Figs. 4, 6, and 7 shows a vertical shaft 76 rotatably mounted in a bore of the housing block 68 which has secured to its bottom end a loop former 77 so shaped that when swung in the direction indicated by the arrow in Fig. 6 it will contact the wire b and bend it about a loop bar 79 which is conveniently located and secured to the under surface of the housing block 68. To impart the desired swinging movement to the loop former 77, the upper end of the vertical shaft 76 has secured thereon a loop former lever 78 which is urged to rotate by a trigger 80

(Figs. 4 and 9) loosely mounted on stud 81 threaded in the side of the straight-motion cam 72. The trigger 80 is yieldingly held in operating position by a spring 82 fastened thereto and to the upper carriage 38. The loop-forming unit, comprising the vertical shaft 76, the loop former 77, and the loop former lever 78, will return to its initial position set by the adjustable stop 83, by the action of a spring 84 fastened to a stud in the loop former lever 78 and to a stud 85 threaded in the top surface of the housing block 68, when permitted by the trigger 80, as shown in Figs. 10 and 11.

A slot 86 near the forward end of the housing block 68 has detachably secured therein a downwardly projecting member 87, at the bottom of which, against the beveled side, the correct location of the binding wire *b* is determined, as shown in Figs. 9 and 10.

The slot 86 also retains therein, by means of a cover plate 88, a vertically reciprocating unit of an inverted-U shape. The upper portion, which is slotted, carries in the slot a roller 90 rotatably mounted on a pin 91 and continually urged against the work surface of the straight-motion cam 72 by the action of a spring 92 coiled about a guide stud 93 and interposed between the bottom of the inverted-U-shaped portion and a bore in the downwardly-projecting member 87, shown clearly in Figs. 4 and 9. As shown in Figs. 10 and 11, the legs of the inverted-U-shaped member 89 are astride the downwardly-projecting member 87 and also a flat member 94 fastened to the inside of the cover plate 88 which has loosely mounted in the bottom portion thereof a flap 95 which is yieldingly held open (see Fig. 9 and broken lines in Fig. 10) by a torsion spring 96 (Fig. 11).

As shown in Figs. 9 and 10, a driver 97, which projects slightly beyond the bottom surface of the legs of the inverted-U-shaped member 89 is securely riveted in slots which are located so that when the prong is properly located against the side of the downwardly-projecting member 87 by the flap 95 which is urged to a closed position by a cross-bar 98 riveted to the outside lower portion of the legs of the inverted-U-shaped member 89, it will be directly in the path of the driver 97.

Referring to Figs. 4, 10, 11, and 14, the upper surface of the lower carriage 29 has permanently secured thereon an upstanding member 99, the uppermost part of which is sufficiently reduced in thickness to provide for shoulders 100, upon which rest blocks 53 secured to the under surfaces of the short bars 52, thus supporting the table unit upon which the work rests during a driving operation. The top surface of the reduced portion of the upstanding member 99 has a lobe 101 shaped thereon, which contacts and urges upward a clincher 102 which is located between the short bars 52 and loosely mounted on a pin 103 secured in the short bars 52.

The operation of the machine is as follows:

With the motor 9 energized, the drive pulley 6 will rotate continuously in a clockwise direction, as indicated by the arrow in Fig. 1; and with the clutch disengaged therefrom, as shown in Fig. 3, the several mechanisms will be at rest in their normal positions, as shown in Figs. 1 and 2. The box part with the wires on the top surface is placed horizontally on a table of desired height in front of the machine. The box part is then moved sidewise from the left to enter between

the housing block 68 secured to the upper extension 5 and the flat cross-members 51 which, with other members, constitute a yieldable support for the work. In moving the box part sidewise, the portion of binding wire *b* projecting beyond the edge of the box part will follow the contour of the forming die 64 (Fig. 8) until correctly located thereon when the body of the binding wire *b* stapled to the box part contacts the downwardly-projecting member 87, as shown in Figs. 9 and 10. With the wire *b* in position, as indicated by dot-and-dash lines in Fig. 6, and the forward edge of the box part located by stop members (Fig. 4) provided for that purpose, the foot treadle 25 is pressed downward, and through appropriate linkage and levers, the brake unit 24 and the clutch buffer 23 are simultaneously released to permit the elements of the clutch to function, causing the clutch band 15 to be thrust into clutching engagement with the surface 7 of the drive pulley 6 to rotate the main shaft 8. The rotation of the cam 28 will urge the lever 34, through its contact with roller 36, to draw the lower carriage 29 toward the rear of the machine or from its position as shown in Fig. 1 to the position shown in Fig. 4, during which the straight-motion cam 58 raises the support block 60 by means of its contact with the roller 61 to sever the wire *b* to correct length by the coaction of the movable knife 63 and the fixed knife 73. Immediately following this, the prong is formed by the upward motion of the forming die 64 against the wire *b*, which is momentarily held and guided by the beveled notch 74 to form the driven portion of the prong, while further upward motion of the forming die 64 presses the wire *b* against the angular forming member 75, thus completing the prong. At this point in the cycle, the upper carriage 38 has moved from its position in Fig. 1 toward the rear of the machine, permitting the trigger 80 to contact the loop former lever 78 (Fig. 4) and has advanced slightly, which has caused the loop former 77 to bend the wire *b* about the loop bar 79.

Continued forward movement of the upper carriage 38 and the straight-motion cam 72 causes the loop former 77 to bend the wire *b* about the loop bar 79 until it is positioned against the inside surface of the downwardly-projecting member 87, at which point the trigger is urged to ascend the beveled top surface of the inverted-U-shaped member 89, thereby releasing the loop former lever 78, which returns to its initial position against the adjustable stop 83 (Fig. 12). Just prior to this movement of the loop former lever 78, the inverted-U-shaped member 89 has been urged downward sufficiently, by the contact of the straight-motion cam 72 and the roller 90, so that the cross-bar 98 has caused the flap 95 to close against the prong. Further forward movement of the straight-motion cam 72, as shown in Fig. 10, 11, and 13, causes the driver 97, which projects slightly beyond the bottom surface of the legs of the inverted-U-shaped member 89 to drive the prong through the box part, since the unit upon which it rests is supported by the blocks 53 of the short bars 52 resting upon the shoulders 100 of the upstanding member 99, which has assumed this position on movement of the lower carriage 29 toward the rear of the machine, which movement is reversed immediately following the driving of the prong. The forward movement of the lower carriage 29 and the

upstanding member 99 causes the lobe 101 to contact the clincher 102, as shown in Fig. 14, clinching the portion of the prong protruding from the under surface of the box part, in the opposite direction from the bight. This completes the fastener operation, as shown in Fig. 15; and the mechanism comes to rest, as shown in Fig. 1. The auxiliary foot treadle 57 is pressed downward, which pulls the work-supporting table down, by means of the connecting link 56, to the position shown in dot-and-dash lines in Fig. 14. By this operation the bight is stripped from the loop bar 79 and the box part may be moved to locate the next wire b.

It should be noted that the cutting, prong-forming, loop-forming, and driving instrumentalities are all located above the box part being operated upon and therefore are adapted to form and perpetuate a loop or bight within the surface area of the box part, i. e., with no portion of the loop or bight extending beyond the edge of the box part.

It should be noted also that said instrumentalities are operated by straight-motion cams.

It will be understood that the invention is not

to be limited to the specific embodiment shown herein for illustration.

I claim:

- 5 1. In a machine for forming and perpetuating a loop or bight on a wire secured to a box part, the combination of a support for the box part and loop-forming instrumentalities comprising means to bend the wire to form a loop and means to drive the end of the wire into a box part to 10 perpetuate the loop; said instrumentalities being located and operable above and within the surface area of a box part positioned on the support, whereby a loop or bight may be formed to lie wholly within the surface area of the box part.
- 15 2. In a machine for forming and perpetuating a loop or bight on a wire secured to a box part, the combination of a support for the box part, loop-forming instrumentalities comprising 20 means to bend the wire to form a loop and means to drive the end of the wire into the box part to perpetuate the loop, and straight-motion cams for operating said instrumentalities.

ALFRED L. ROSEN MUND.
